UNITED STATES PATENT OFFICE

PETER McILROY, OF ALLISON PARK, PENNSYLVANIA, ASSIGNOR TO ENAMELED METALS COMPANY, OF SHARPSBURG, PENNSYLVANIA, A CORPORATION OF PENNSYLVANIA.

PROTECTOR FOR PIPES OR CONDUIT UNITS.

1,165,427.

Specification of Letters Patent. Patented Dec. 28, 1915.

Application filed March 4, 1915. Serial No. 11,997.

To all whom it may concern:

Be it known that I, PETER McILROY, a citizen of the United States, and a resident of Allison Park, in the county of Allegheny and State of Pennsylvania, have invented a new and useful Improvement in Protectors for Pipes or Conduit Units; and I do hereby declare the following to be a full, clear, and exact description thereof.

10 My present invention pertains to new and useful improvements in protectors for the threaded terminals of pipe or conduit units.

The principal object of my invention is to provide a novel form of metallic protecting sleeve, which may be quickly positioned to ensheathe a fragile protecting sleeve, which is in direct engagement with the threads of the pipe.

20 An object of equal importance is to form on the metallic protecting sleeve a closure wall which will serve to seal the end of the conduit unit when the sleeve is applied thereto.

Another object of my invention is to so 25 form the metallic protecting sleeve that while it will thoroughly guard against injury to the fragile protector through contact with foreign objects, and will be capable of being quickly and securely attached, 30 it may nevertheless be removed with relative ease by screw driver, a pair of pliers, or any similar tool, such as workmen use while on a job.

The above and other incidental objects of 35 a similar nature, which will be hereinafter more specifically disclosed, are accomplished by such means as are illustrated in the accompanying drawings, described in the following specification, and then more particularly pointed out in the claims, which are appended hereto and form a part of this application.

With reference to the drawings wherein there has been illustrated the preferred embodiment of this invention, as it is reduced to practice, and throughout the several views of which similar reference numerals designate corresponding parts:

Figure 1 is a longitudinal section of a 50 coated pipe or conduit unit embodying my invention. Fig. 2 is a transverse section; Fig. 3 shows the thread protector in longitudinal cross-section; Fig. 4 is an end view of the protector; Fig. 5 is a longitudinal

section showing a modified protector applied 55 to a conduit unit; Fig. 6 is a detail section of the protector of Fig. 5; Figs. 7 and 8 are side views of other forms of the metallic protector.

As illustrated in the accompanying drawings the metallic protecting sleeve is designated as an entirety by the numeral "A", and it is applied to one terminal of the length of pipe 10 to embrace or ensheathe the fragile protector 11 thereon. The protector 60 11 is of the type disclosed in my Letters Patent No. 1,120,731, dated December 15th, 1914, and is formed of paper, linen, pulp or some similar material. These protectors are applied to pipes which are provided with an 65 interior and exterior coating thereon, as at *a*, and are employed to keep the threads of the pipe clean during such coating, transit and storage; such coated pipes being also provided with the coupling *b* on the other 70 terminal of the pipe, and which is also coated with the pipe.

It has been found that in some instances, as when the fragile protectors are subject to rough handling in transit, that they become 75 broken and fall away from the threads. With the metallic protecting sleeve A, however, such an occurrence is well guarded against, for as will be readily observed, the sleeve A not only protects the face of the 80 fragile sleeve, but also the outer end thereof. Specifically the member A consists of the annular body portion 13, the laterally 85 extending annular flange 14, the inwardly directed flange 15, which extends at an obtuse angle to the member 14 and parallel to the member 13, and the closure wall 16 which extends at right angles to the member 13.

The member 15 is obtusely directed in order 90 to assure the application of the protector in the proper manner to standard piping in which, as it is well known, the internal diameters of various pieces of the same external diameter vary.

An improvement function of the closure wall 16 is to seal the end of the pipe or conduit unit to which the protector is applied. Thus a conduit unit equipped with the member A is protected against injury to its 100 threads and against the entrance of mud or dirt of any kind into its interior, and its coupling threads and its interior are further

protected by the use of a removable closure member 20, such as shown in Fig. 1, which member 20 also protects the end of the coupling by its roll edge end 21 fitting against said coupling and outer end. This member 20 is formed of tin or other light metal and is provided with the threaded portion 22 for engaging the threads of the coupling and which connect with the end 21 and with the closure wall 23 within the coupling. It is removed by unscrewing the same in catching the rolled edge 21.

In the modified form of the invention shown in Figs. 5 and 6, the body member 13 and flange 14 are rolled to form the annular beads 18 and 19 respectively. These beads thoroughly protect the end of the fragile protector to which the member A is applied, for an object encountered by either 20 the side or end of the pipe will do little damage since the rings or beads will act as buffers.

The metallic protector or member A may be held in place, after being positioned on 25 the protector 11, by forming indentations 21 in the flange 13 thereof as shown in Figs. 7 and 8 which take into the protector 11, and when it is desired to remove the metallic protector it is only necessary to use a tool in 30 a slit 24 such as is shown in Fig. 4, or grasp the member 13 with a pair of pliers or the like and to pull off the protector in an obvious manner.

As shown in Fig. 3, the inner space defined by the members 13, 14 and 15 may be utilized as a receiving chamber for a ring buffer 17. This member 17 is formed preferably of cork or paper, although any other material of the same general nature may be 40 employed. It will be seen that by inserting the member 17 between the end of the pipe and the flange 14, the end thread of the pipe is thoroughly protected against injury in case the end of the pipe strikes or is struck 45 by a foreign object while in transit or storage.

In reduction to practice, I have found that the form of my invention, illustrated in the drawings and referred to in the above 50 description, as the preferred embodiment, is the most efficient and practical; yet, realizing that the conditions concurrent with the adoption of my device will necessarily vary, I desire to emphasize the fact that various 55 minor changes in details of construction, proportion and arrangement of parts may be resorted to, when required, without sacrificing any of the advantages of my invention, as defined in the appended claims.

60 What is claimed is:

1. As a new article of manufacture, the combination with a conduit having a threaded end and a fragile thread-protecting member associated with said threaded end, said 65 thread-protecting member being adapted to

be broken away from the threads of said end when the conduit is to be used, of a metallic protector associated with said thread-protecting member at the side thereof remote from the threads. 70

2. As a new article of manufacture, the combination with a conduit having a threaded end and a fragile thread-protecting member associated with said threaded end, said thread-protecting member being adapted to 75 be broken away from the threads of said end when the conduit is to be used, of a metallic cap covering the end of said thread-protecting member, thereby to protect said member and close the end of the conduit. 80

3. As a new article of manufacture, the combination with a conduit having a threaded end and a fragile thread-protecting member associated with said threaded end, said thread-protecting member being adapted to 85 be broken away from the threads of said end when the conduit is to be used, of a metallic protector associated with said thread-protecting member at the side thereof remote from the threads, said metallic protector being capable of easy removal from said member. 90

4. As a new article of manufacture, the combination with a conduit having a threaded end and a fragile thread-protecting member associated with said threaded end, said thread-protecting member being adapted to 95 be broken away from the threads of said end when the conduit is to be used, of a metallic cap covering the end of said thread-protecting member, thereby to protect said member and close the end of the conduit, said cap having a central indented portion entering 100 the end of the conduit. 100

5. As a new article of manufacture, the combination with a conduit having a threaded end and a fragile thread-protecting member associated with said threaded end, said thread-protecting member being adapted to 105 be broken away from the threads of said end when the conduit is to be used, of a metallic cap covering the end of said thread-protecting member, thereby to protect said member and close the end of the conduit, said cap having a central indented portion entering 110 the end of the conduit, said cap being capable of easy removal from said member. 115

6. An interiorly and exteriorly coated pipe or conduit unit provided with threads at its terminals, a coupling connected to one of said terminals and provided with a closure member, a fragile thread protector on the other terminal, and a removable metallic cap associated with said thread protector for 120 protecting the latter. 125

7. The herein described process of forming pipes or conduit units having threads at their terminals, consisting in the steps of 130 applying a protecting sleeve of soft ma-

terial to one of said terminals, applying a protector of hard and thin material over said first named protector to close the end of the pipe or unit, and indenting said last 5 named protector to permit the same to take into said first named protector to hold the second protector in place.

8. The herein described process of forming pipes or conduit units having threads at 10 their terminals, consisting in the steps of applying a protecting sleeve of fragile soft

material to one of said terminals, and applying a protector of hard and thin material over said protecting sleeve to close the end of the pipe or unit.

In testimony whereof, I the said PETER McILROY have hereunto set my hand.

PETER McILROY.
